UNITED STATES PATENT OFFICE.

NICHOLAS L. KUHNEN, OF ELKHART, INDIANA.

DESIGN FOR A CHAIR.

Application filed November 19, 1925. Serial No. 15,465. Term of patent 3½ years.

To all whom it may concern:

Be it known that I, NICHOLAS L. KUHNEN, residing in the city of Elkhart, county of Elkhart, Indiana, have invented a new and original and ornamental Design for a Chair, of which the following is a specification, reference being had to the accompanying drawing, forming a part hereof.

The figure is a front elevation view of the chair, showing my new design.

I claim:

The ornamental design for a chair, as shown.

In witness whereof I have hereunto affixed my signature this 17th day of Nov., 1925.

NICHOLAS L. KUHNEN.
